PISTON

Percy L. Bowser, University City, William M. Venner, Richmond Heights, and Percy L. Bowser, Jr., University City, Mo., assignors to The Sterling Corporation, St. Louis, Mo., a corporation of Delaware

Application May 16, 1938, Serial No. 208,184

2 Claims. (Cl. 309—13)

This invention pertains to trunk pistons such as are used in internal combustion engines and more particularly the pistons constructed of light metals such as aluminum, magnesium and alloys thereof.

One of the objects of this invention is to provide a piston of novel structure having means for restraining the thermal expansion thereof in the direction of the piston diameter.

Another object is to provide a light metal piston of this type having means of a lower coefficient of expansion applied in such a manner as to restrain expansion of the skirt diameter.

Another object is to provide novel means whereby the expansion of the piston head may be applied through connecting means to restrain expansion of the piston skirt.

Further objects will appear from the following description taken in connection with the accompanying drawings in which—

Figure 1 is a longitudinal section of a piston embodying this invention.

Figure 2 is a side view of the same showing one of the bearing sections thereof.

Figure 3 is a side view taken from the end of the wrist pin axis.

Figure 4 is a longitudinal section taken transversely of the wrist pin axis.

Figure 5 is a half section taken transversely of the piston through the wrist pin axis.

Figure 6 is a side view taken along the wrist pin axis of a piston illustrating another embodiment of this invention.

Figure 7 is a longitudinal half section along the wrist pin axis of the piston of Figure 6.

Figure 8 is a longitudinal section of the same taken transversely to the wrist pin axis.

Figure 9 is a transverse section of the same taken on line 9—9 of Figure 7, and

Figure 10 is a developed view of the controlling element or band of the piston of Figure 6.

Referring to the drawings, the piston illustrated is of the trunk type having a head 1 and a skirt indicated generally at 2. The skirt may be considered as comprising a lower circumferential rim 3 from which cylinder bearing sections 4 extend upwardly toward the piston head. The bearing sections 4 are each separated from the head 1 by a horizontal slot 5 which may be cast in the piston but which is usually formed by a saw cut after the piston has been cast. A pair of piers or connectors 6 extend downwardly from the head, integrally connecting the head with the skirt, and with wrist pin bosses 7 formed at the lower ends of said piers or connectors.

Said connectors may be stiffened by reinforcing ribs 8 extending therealong.

In the embodiment illustrated in Figures 1 to 5, inclusive, the two bearing sections 4 are formed separate from the connectors 6 by providing intervening gaps 9. An expansion controlling element in the form of a flexible band 10 is arranged to connect the sections 4 with the connectors 6. In Figures 1 to 5, this band is shown as a complete hoop extending around the interior of the skirt and cast into the outer portions of the bosses 7, as shown in Figure 5, and into the middle portion only of the sections 4. The connection of the band 10 to the sections 4 may be made by means of a narrow internal rib 11 extending along the middle portion only of the sections 4 and having portions of the cast metal extending through openings in the band 10 as indicated at 12 in order to provide a secure connection between the band and the cast metal.

The band 10 is preferably constructed of material having a lower co-efficient of thermal expansion than that of the piston metal. It has been found that for an aluminum piston, a band of steel provides a satisfactory controlling member. As shown in Figure 5, this band extends around the interior of the skirt in a nearly circular form and is imbedded in the bosses 7 as near their outer ends as possible.

In the embodiment shown in Figures 6 to 10, only one of the bearing sections 4 is formed separate from the connectors 6, the other section being integrally connected with the piers or connectors so as to be rigidly supported thereby. In this embodiment, the control member shown at 10' is arranged to form approximately a semi-circle extending around that side of the skirt on which the bearing section is separate from the connectors 6. In this embodiment the band may be provided with openings or notches 12' adapted to receive the cast metal 12. The ends of the band may be recessed as indicated at 13 where they are imbedded in the bosses 7 so as to surround the wrist pin opening. The ends 14 of the band may be bent inwardly, as shown in Figure 9, so as to provide a secure inter-lock where they are imbedded in the bosses 7. These ends may be arranged to project inwardly from the casting to a slight extent, the projecting ends being set into shiftable receiving notches in the mold core in which the piston is cast so as to support the band in place in the mold for casting the piston around it.

When the piston is cast the skirt is usually

cast solid with the head, that is, without the slot 5. When the casting cools, the contraction of the piston metal is usually greater than that of the band 10. Furthermore, the metal of the skirt usually sets somewhat before the metal of the head becomes solid so that there is a lag in the cooling temperature of the head behind that of the skirt. As a consequence, the head contracts after the skirt has solidified and, accordingly, there is an inward tension placed upon the skirt by the contraction of the head. Since the band 10 is within the skirt, it is subjected to compression during such cooling. When now the slot 5 is cut, the skirt is freed from the head and springs outwardly with respect thereto on account of the release of this inward tension. This action tends to produce a slight clearance between the skirt section 4 and the band 10 at the points indicated by the numeral 15. Accordingly, the section 4 is supported at its middle portion and relatively free at its side edges so that it may twist or warp to a certain extent in order to accommodate itself to the pressure of the cylinder wall.

The outer bearing surface of the skirt may be machined to a slightly oval form with the minor axis of the oval in a direction parallel to the wrist pin axis. The skirt surface may also be relieved in the regions of the ends of the bosses 7, as indicated at 16. This piston may be given a fairly snug fit in the cylinder across the diameter of the faces 4. A clearance as small as one-thousandth of an inch on the diameter has been used successfully. When the piston is in service, the heat of combustion is applied to the piston head and transmitted therefrom to the skirt. The head usually expands to a greater extent than the skirt. This expansion of the head carries with it the connectors 6 and the bosses 7 to the outer portion of which the band 10 or 10' is connected. Such expansion of the bosses, therefore, tends to stretch the band along the wrist pin axis and therefore to contract its diameter on the transverse axis. This causes the band to exert a tension upon the skirt sections 4 connected thereto so as to draw them inwardly and compensate for the tendency of these portions of the skirt to expand radially. By proper adjustment, this tendency can be compensated almost exactly so that a uniform fit of the skirt in the cylinder may be maintained. It will be noted that on account of the springing out of the sections 4, as described above, the band curvature is slightly increased at the point of connection to the section 4. Furthermore, since the point of connection of the band to the bosses 7 is at their outer portion, the maximum expansion along the wrist pin axis is effective to stretch the band, and since the portions thereof intervening between the bosses and the connecting point to the sections 4 are nearly straight, the stretching thereof acts with a sort of toggle action to draw inwardly the skirt sections 4.

It will be seen, therefore, that a piston structure is provided by which the tendency for the piston to expand at a greater rate than the cyl-

inder in which it operates is corrected by providing a control member of a less co-efficient of expansion connected so that the expansion along the wrist pin axis is applied through this member to restrain expansion of the skirt along the transverse axis.

While a certain theory of operation has been set forth above, it will be understood that this is for the purpose of clarity in explanation and that it is not intended to set up any particular theory of operation as a basis for this invention. It is further understood that various individual features or sub-combinations of the piston, as illustrated and described, may be found useful by themselves without reference to other features or the complete combination, and the employment of such individual features or sub-combinations is contemplated by this invention and within the scope of the appended claims.

It is further obvious that changes may be made in the details of construction within the scope of the appended claims without departing from the spirit of this invention; it is understood, therefore, that the invention is not limited to the specific details shown and described.

Having thus described the invention, what is claimed is:

1. A trunk piston of the character described having a head and a skirt, wrist-pin bosses on said skirt, rigid connectors joining said head integrally to said skirt and said bosses, said skirt having cylinder-bearing sections in the regions between said bosses one of which sections is integrally connected with said bosses while the other is separate therefrom, both of said sections being separated from said head, said head and skirt being constructed of a material having a high coefficient of thermal expansion, and a flexible band of material having a lower coefficient of thermal expansion anchored to the outer portions of said bosses and connected to the middle portion only of said separate cylinder-bearing section in order to transmit thereto expansion of said bosses in a direction such as to restrain expansion of said section.

2. A trunk piston, comprising, a head, a skirt, wrist-pin bosses, connectors integrally connecting said skirt and said bosses with said head, said skirt having cylinder-bearing sections in the regions between said bosses, said sections being separated from said head and one of said sections being separate from said connectors, said head and skirt being constructed of material having a high coefficient of thermal expansion, and a flexible band of material having a lower coefficient of thermal expansion anchored to the outer portions of said bosses and connected to the middle portion only of said separate section in order to transmit thereto expansion of said bosses in a direction such as to restrain expansion of said section, said band lying wholly inwardly of said section except at the connection thereof, and being formed with a greater curvature than said section.
